(57) **CLAIM**

The ornamental design for a base for electronic personal assistant, as shown and described.

DESCRIPTION

FIG. 1 is a perspective view of a base for electronic personal assistant, showing our new design with an environmental electronic personal assistant;

FIG. 2 is a perspective view of the base of FIG. 1, shown isolated for clarity;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top view of thereof; and,

FIG. 8 is a bottom view thereof.

The broken lines in FIG. 1 depict environmental subject matter only and forms no part of the claim, while all other broken lines in the drawings depict portions of the base for electronic personal assistant that form no part of the claimed design.

1 Claim, 6 Drawing Sheets
